United States Patent

Des. 235,569
Patented June 24, 1975

235,569

TOY BANK

Angelo L. De Fina, 2882 86th St., Brooklyn, N.Y. 11223

Filed Sept. 20, 1973, Ser. No. 399,105

Term of patent 14 years

Int. Cl. D31—00

U.S. Cl. D34—11 R

FIG. 1

FIG. 2

FIG. 3

FIG. 4

FIG. 5

FIG. 1 is a front perspective view of a toy bank showing my new design;

FIG. 2 is a rear perspective view thereof;

FIG. 3 is a left side perspective view thereof;

FIG. 4 is a top plan view thereof; and

FIG. 5 is a front perspective view of another embodiment thereof.

I claim:

The ornamental design for a toy bank, substantially as shown and described.
